WEDGE ANCHOR FOR TENSIONING AND ANCHORING WIRES

Lultcho Boduroff, Denver, and Homayoun J. Meheen, Cherry Hills Village, Colo., assignors to B & M Prestress Corp., Englewood, Colo.

Filed Jan. 18, 1960, Ser. No. 2,838
19 Claims. (Cl. 24—122.6)

This invention comprises a novel and useful wedge anchor for tensioning and anchoring wires and more particularly relates to a means for post tensioning structures, and especially those of a concrete nature.

The principal object of this invention is to provide a means whereby prestressing wires may be effectively post tensioned and securely anchored under tension in a building structure.

A further object of the invention is to provide a means whereby a plurality of prestressing wires may be securely anchored and post tensioned in concrete members.

A further object of the invention is to provide a small compact anchoring means whereby a plurality of prestressing wires may be post tensioned and anchored as prestressing for various structural elements.

A still further object of the invention is to provide a means whereby a plurality of prestressing wires disposed in side-by-side arrangement may be securely anchored and post tensioned in building structures and wherein the loads applied to the prestressing wires will be effectively distributed between the same.

Yet another object of the invention is to provide a prestressing wire and anchor construction whereby a single anchor fitting and its locking means shall be effective for effectively anchoring and securing under tension a plurality of prestressing wires in which the number of wires is subject to variation and the arrangement of the wires is likewise variable.

A further and specific object of the invention is to provide an anchoring means for the post tensioning of prestressing wires which shall effect an improved gripping action upon the wires, will maintain the wires in a spaced relation with respect to each other, and will have a positive gripping and non-slipping action upon the wires.

Still another object of the invention is to provide an apparatus whereby a plurality of prestressing wires may be selectively post tensioned and then securely anchored.

These together with other objects and advantages which will become subsequently apparent reside in the details of construction and operation as more fully hereinafter described and claimed, reference being had to the accompanying drawings forming a part hereof, wherein like numerals refer to like parts throughout, and in which:

FIGURES 1-7 relate to a preferred form of anchoring means for post tensioned prestressing wires and in which:

FIGURE 1 is a perspective view, partly broken away and shown in section of the anchoring means by which a plurality of prestressing wires are anchored under tension in accordance with the invention;

FIGURES 2 and 3 are perspective views of one of the anchoring wedges employed in the arrangement of FIGURE 1;

FIGURE 4 is an end elevational view taken from the left end of FIGURE 1 but with the prestressing wires omitted therefrom;

FIGURE 5 is an end elevational view taken from the right end of FIGURE 1 but with the prestressing wires omitted therefrom;

FIGURE 6 is a vertical longitudinal sectional view through the anchoring means of FIGURE 1 being taken substantially upon the plane indicated by the broken section line 6—6 of FIGURE 5; and

2

FIGURE 7 is a vertical transverse sectional detail view taken substantially upon the plane indicated by the section line 7—7 of FIGURE 6.

Referring now to the embodiment of FIGURES 1-7 which constitutes a preferred embodiment in accordance with the principles of this invention, it will be observed that the numeral 10 designates generally the anchor by which a plurality of prestressing rods or similar elements 12 are locked in position and under tension through the agency of a plurality of locking wedges each designated generally by the numeral 14.

The anchor 10 comprises a metallic cylindrical body 16 having a laterally projecting anchoring flange 18 at one end thereof. The body is provided with a conical locking surface 20 extending axially therethrough, the larger end of this bore 20 emerging upon the surface of the anchoring flange 18, while the smaller end of the bore opens at the other end of the body. The bore is preferably circular in cross-section and there are provided a series of complementary locking wedges 14, six being considered quite satisfactory for the purposes of this invention. These locking wedges are of a particular construction for the purpose of this invention.

Referring now especially to FIGURES 2 and 3 it will be observed that each of the locking wedges 14 has a convex outer surface 22 which is complementary to the conical locking surface of the bore 20 of the body 16 together with a pair of planar radially extending side surfaces, each designated by the numeral 24 while the smaller inner edge of the wedge 14 has a flat surface 26.

Upon each of the two side faces there is provided a semi-cylindrical channel or groove as at 28 which, as shown in FIGURES 1, 6 and 7 are adapted to receive the prestressing wires or elements 12 therebetween. The depth of these channels are slightly less than the radius of the prestressing wires or elements 12 in order that when the wires are disposed in the complementary grooves or channels of the adjacent planar faces 24 of adjacent wedges, and the wedges forced radially inward or against each other, the faces 24 of adjacent wedges will be slightly spaced to thereby cause the surfaces of the registering complementary channels of adjacent wedges to tightly frictionally grip and lock the prestressing wires or elements 12 therebetween. At the same time, there is provided a central space through the series of wedges and extending axially of the bore 20 which provides a clearance to permit radial movement of the wedges in the bore as the wedges, when shifted longitudinally of the bore are forced toward each other.

The outer convex face 22 of each wedge has a longitudinally extending medial groove or channel 29 of a depth slightly less than the diameter of a wire or rod 12 for receiving the latter and wedging it tightly against the surface of the bore 20 when the wedges are driven into place.

Preferably the thicker or outer ends of the locking wedges 14 have flat surfaces 30 while similar surfaces 32 may be provided upon the inner edges of these wedges. The outer surfaces are employed to receive the pressure of a suitable tool, such as that shown in FIGURES 16-21 and described hereinafter, whereby the wedges will be forced inwardly of the bore 20 and into locking engagement with the prestressing wires or elements.

The anchor 10 is specifically adapted for disposition in a recess or socket in the end of a concrete member or other structural element, it being understood that a suitable bore extends through the beam or element for the reception of the tensioning members 12. However, the precise manner in which the anchor 10 and its anchoring flange 18 is secured to the structural member for which the reinforcements 12 are intended, is in itself not critical for the purpose of this invention.

In operation, it will be understood that with the anchor body 16 positioned in proper relation upon the structural element for which the prestressing is intended, and with the prestressing wires 12 being disposed through the bore 20 of the anchor, and suitably post tensioned, with the locking wedges 14 being loosely received in the bore 20 and seating the prestressing wires 12 therebetween, the locking wedges 14 are driven into the bore 20 until the conical bore forces the wedges circumferentially toward each other and radially towards the bore 20 and thereby causes the wedges to frictionally grip and return the tensioned elements 12. When this condition occurs, it is obvious that in view of the extensive surface to surface contact with the prestressing elements with the wedges, and of the wedges with the bore 20, and when the tensioning means is disengaged from the prestressing wires 12, that the latter will in turn have their tension imparted to the wedges. Thus a self-locking structure is provided, inasmuch as any extra or additional pull from one of the wires will result in further increasing the locking action 20 of the entire assemblage.

In the arrangement illustrated in FIGURES 1-7 the locking wedges can receive, retain and anchor a maximum of twelve or more of the wires or elements 12. However, it is evident that the same construction can 25 satisfactorily lock in post tensioned position any number of wires from two to ten inclusive or twelve wires by appropriately distributing the prestressing wires between the six sets of locking channels of the wedges and between the two concentric rows of radially spaced locking channels. The two sets of channels 28 and 29 are radially spaced and staggered circumferentially of each other to effect a uniform distribution and spaces of the elements 12 from each other.

It is further evident that more than six radially locking channels may be used to anchor a greater number of prestressing elements than the twelve shown in FIGURES 1-7.

The foregoing is considered as illustrative only of the principles of the invention. Further, since numerous 40 modifications and changes will readily occur to those skilled in the art, it is not desired to limit the invention to the exact construction and operation shown and described, and accordingly all suitable modifications and equivalents may be resorted to, falling within the scope 45 of the invention as claimed.

What is claimed as new is as follows:

1. An anchor for tensioned prestressing elements comprising an elongated body having an opening extending entirely therethrough, said opening having a central longitudinal axis with the wall of said opening being tapered from end to end, a plurality of prestressing elements each having a straight and nontwisted portion, said portions being disposed within said opening in circumferentially spaced side-by-side relation about said axis, a plurality of wedges disposed in said opening in circumferentially spaced side-by-side relation about said axis and each disposed between a pair of adjacent element portions, adjacent surfaces of adjacent wedges having registering pairs of complementary rectilinear channels, each pair of registering channels being of sufficient cross-sectional area to receive and to compressively grip and retain therein the straight portion of a single prestressing element in a twist free condition, said channels being spaced from said opening wall, said wedges having other surfaces cooperating with said opening wall for squeezing said wedges and their associated registering channels towards each other when the wedges are forced axially of said body opening.

2. The combination of claim 1 wherein said channels are of uniform cross-sectional area and shape throughout their length and are smooth and free of projections upon their complementary registering surfaces.

3. The combination of claim 1 wherein said body opening wall is frusto-conical.

4. The combination of claim 1 wherein the longitudi-

nal axes of said registering channels are mutually divergent from the smaller diameter to the larger diameter of said body opening.

5. The combination of claim 1 wherein the longitudinal axes of said registering channels are spaced uniformly from each other and are equidistant from said central longitudinal axis.

6. The combination of claim 1 wherein the longitudinal axes of said registering channels are disposed in opposed pairs on opposite sides of said central longitudinal axis and are spaced from each other and are equidistant from the wall of said opening.

7. The combination of claim 1 wherein said elements are disposed in balanced relation about said central longitudinal axis wherein their tensions will be balanced about the latter.

8. The combination of claim 1 wherein said wedges have a length substantially equal to that of said opening.

9. The combination of claim 1 wherein said wedges are of such length as to engage said opening wall over substantially the entire length of the latter.

10. The combination of claim 1 wherein said wedges are cut away along one surface thereof to provide a clearance between said wedges and the said central longitudinal axis.

11. The combination of claim 1 wherein said wedges are generally arcuate in transverse section and have outer arcuate faces cooperatively engaging said opening wall.

12. The combination of claim 1 wherein said wedges are disposed in sets of circumferentially spaced wedges, each set having its wedges so positioned about said central longitudinal axis as to produce a balanced tension about the latter.

13. The combination of claim 1 wherein said wedges include outer faces which are transversely arcuate and have a cooperating wedging and sliding engagement with said opening wall, said outer faces having each a straight, longitudinally extending recess therein, one of said element portions being received in each of said recesses and compressively clamped therein between said recess and opening wall.

14. The combination of claim 1 wherein said wedges include outer faces which are transversely arcuate and have a cooperating wedging and sliding engagement with said opening wall, said outer faces having each a straight, longitudinally extending recess therein, one of said element portions being received in each of said recesses and compressively clamped therein between said recess and opening wall, said recesses being circumferentially spaced from said registering channels.

15. The combination of claim 1 wherein each wedge has a transversely arcuate outer face cooperatively and wedgingly engaging said opening wall and a planar inner face spaced from said central longitudinal axis together with a pair of planar side faces, said side faces having said registering channels therein.

16. The combination of claim 1 wherein each wedge has a transversely arcuate outer face cooperatively and wedgingly engaging said opening wall and a planar inner face spaced from said central longitudinal axis together with a pair of planar side faces, said side faces having said registering channels therein; each of said faces extending the length of said opening and said outer faces having continuous engagement with the opening wall throughout the length of the latter.

17. The combination of claim 1 wherein each wedge has a transversely arcuate outer face cooperatively and wedgingly engaging said opening wall and a planar inner face spaced from said central longitudinal axis together with a pair of planar side faces, said side faces having said registering channels therein, each of said outer faces having a longitudinally extending, straight medially disposed recess therein, each recess receiving and compressively re-

taining one of said element portions therein and against said opening wall.

18. The combination of claim 1 wherein said body is provided with an externally projecting mounting flange, the outer surface of said mounting flange and the adjacent end of said body being coplanar whereby the inner surface of said mounting flange will be abutted against the outer surface of an article when said body is completely embedded in the latter.

19. The combination of claim 1 wherein said body is provided with an integral externally projecting mounting flange at one end and completely surrounding said body, said opening in said body being convergently tapering from said mounting flange to the other end of said body whereby said mounting flange may be engaged with the outer surface of an object in which said elements are dis-

posed when said body is completely embedded in said object.
